US0D1030715S

(12) **United States Design Patent** (10) **Patent No.:** **US D1,030,715 S**
Barad et al. (45) **Date of Patent:** **** Jun. 11, 2024**

(54) **INPUT DEVICE WITH DISPLAY**

(71) Applicants: **Justin Barad**, New York, NY (US);
Jordan Christopher, Marina Del Rey, CA (US); **Michael Cherkezian**, New York, NY (US)

(72) Inventors: **Justin Barad**, New York, NY (US);
Jordan Christopher, Marina Del Rey, CA (US); **Michael Cherkezian**, New York, NY (US)

(**) Term: **15 Years**

(21) Appl. No.: **29/852,963**

(22) Filed: **Sep. 12, 2022**

(57) **CLAIM**

The ornamental design for a input device with display, as shown and described.

DESCRIPTION

FIG. 1 is a perspective view of an input device with display in accordance with the present invention;

FIG. 2 is a top plan view thereof;

FIG. 3 is a bottom plan view thereof;

FIG. 4 is a rear elevation view thereof;

FIG. 5 is a front elevation view thereof;

FIG. 6 is a right side elevation view thereof; and,

FIG. 7 is a left side elevation view thereof.

The broken lines showing portions to the article form no part of the claimed design.

1 Claim, 4 Drawing Sheets
